UNITED STATES PATENT OFFICE

132,553

DESIGN FOR A GOLF CLUB HEAD

John Cowan, deceased, late of Belmont, Mass.,
by Jeanie Cowan, executrix, Belmont, Mass.

Application February 2, 1938, Serial No. 74,806

Term of patent 7 years

To all whom it may concern:

Be it known that I, Jeanie Cowan, a citizen of the United States and a resident of Belmont, county of Middlesex and State of Massachusetts, executrix of the estate of John Cowan, deceased, who it was found invented a new, original, and ornamental Design for a Gold Club Head, of which the following is a specification, reference being had to the accompanying drawing, forming part thereof.

In the drawing:

Fig. 1 is a top plan view of a golf club head showing my new design,

Fig. 2 is a side elevational view, and

Fig. 3 is an end elevational view.

I claim:

The ornamental design for a golf club head, as shown.

JEANIE COWAN,
Executrix of the Estate of John Cowan, Deceased.
